(57) CLAIM

The ornamental design for a memo paper dispenser, as shown and described.

DESCRIPTION

The new invention is to provide a new design for common “memo paper dispenser”, especially referring to the combination of adhesive memo papers dispenser with a modern design, which provides a decorative look and at the same time, allows the user the easy access to the memo paper.

FIG. 1 is a front view of a memo paper dispenser showing my new design;

FIG. 2 is a rear view thereof;

FIG. 3 is a left side view thereof;

FIG. 4 is a right side view thereof;

FIG. 5 is a top plan view thereof;

FIG. 6 is a bottom plan view thereof; and,

FIG. 7 is a perspective view thereof.
